FLUE DAMPER WITH LATCHING MEANS

Augustus P. Terry, Berkeley, Calif.

Application February 21, 1949, Serial No. 77,475

6 Claims. (Cl. 126—285)

1

This invention relates to and in general has for its object the provision of a latching mechanism for locking the damper of a flue in its closed position.

More specifically, the object of this invention resides in the provision of a flue controlled by a damper pivoted therein for rotation on a horizontal axis and wherein the damper can be locked by means of a latch mounted on the flue adjacent one of the free edges of the damper for limited travel along a fixed vertical axis and for rotation thereon in response to the movement of the damper.

The invention possesses other advantageous features, some of which, with the foregoing, will be set forth at length in the following description where those forms of the invention which have been selected for illustration in the drawings accompanying and forming a part of the present specification are outlined in full. In said drawings, three forms of the invention are shown, but it is to be understood that it is not limited to such forms, since the invention as set forth in the claims may be embodied in a plurality of forms.

Referring to the drawings:

Fig. 1 is a vertical mid-section of a damper controlled flue provided with a latching mechanism embodying the object of my invention.

Fig. 2 is an isometric view of the latching mechanism shown in Fig. 1 in side elevation.

Fig. 3 is a front elevation of the latching mechanism illustrated in Figs. 1 and 2.

Fig. 4 is an illustration of a blank from which the bracket and cam track of my latching mechanism can be formed.

Fig. 5 is a perspective view of a modified form of latching mechanism embodying the object of my invention.

Fig. 6 is a perspective view of a still further modification of the latching mechanism shown in Figs. 1—5 inc.

All three modifications of the latching mechanism shown in the above figures are used in conjunction with a flue 1, in which is journaled on a diameter thereof a horizontally extending shaft 2. Fixed to the shaft 2 is a damper 3 provided on its lower, right-hand end as shown in Fig. 1 with an eye 4 through which a cable, cord or chain 5 can be attached.

Riveted to the left-hand side of the flue 1 in a vertical plane containing that diameter of the flue which bisects the shaft 2 is a bracket generally designated by the reference numeral 6. The bracket 6 includes opposed upper and lower

inwardly extending arms 7 and 8 and a cam blank 9. Journaled in the outer ends of the upper and lower arms 7 and 8 is a latch stem 11 and formed in the cam blank 9 is a tortuous cam track generally designated by the reference numeral 12. The cam blank 9 is formed substantially into a cylinder surrounding the stem 11 and extending diametrically through the latch stem 11 is a cam follower pin 13. The lower wall of the cam track 12 starting from its right-hand end as shown in Fig. 2, or from its left-hand end as shown in Fig. 4, includes a fall 14 terminating in a notch 15, a rise 16 terminating in a point or apex 17, a fall 18 terminating in a notch 19, and a rise 21 terminating in an apex 22. For all practical purposes the apex 22 merges with the fall 14 even though the free edge of the cam blank does not form a complete cylinder with its opposite end. Although in general the profile of the upper wall 20 of the cam track 12 is complementary to the profile of its lower wall, it is to be particularly noted that the notch or apex 15a of the upper profile is slightly offset to the left as viewed in Fig. 4 with respect to the notch 15 of the lower profile. Similarly, the notch 17a of the upper profile is slightly offset to the right with respect to the apex 17 of the lower profile and the apex 19a of the upper profile is slightly offset to the left with respect to the complementary notch 19 of the lower profile. As will be presently more fully explained, this construction is essential to insure that the latch stem 11 always rotates in a clockwise direction as viewed in Figs. 1, 2 and 3 in response to each upward and downward travel of the stem.

The lower end of the stem 11 terminates in a point or teat 23 and mounted immediately above this teat 23 is a sector-shaped latch 24 subtending an angle of slightly less than 180°. Mounted on the left-hand side of the damper 3 immediately adjacent the locus of the latch 24 is a spacing member 25 and formed integral with this spacing member is a catch or keeper 26 with which the latch 24 is arranged to engage when the latter assumes an inwardly directed position.

Assuming as shown in Fig. 1 that the damper is in its closed and latched position and that it is desired to open the damper, the right-hand end of the damper 3 is pulled downwardly by the cable 5, thereby causing the left-hand end thereof to rise and engage the teat 23 of the latch stem 11. The latch stem moves upwardly under the influence of the upward movement of the damper. Momentarily, the follower pin 13 only moves vertically away from its seat in the notch

19 of the lower profile of the cam track without any rotary movement. However, upon its continued upward travel it engages the complementary rise of the upper profile immediately to the left of the point or apex 19a thereof. The further upward travel of the stem 11 is therefore accompanied by a clockwise rotation during that time that the follower pin is traveling in engagement with the rise of the profile immediately to the left of the apex 19a. As a result of this movement the stem 11 turns through an angle of about 90°. By this time the left-hand end of the damper is moving downwardly under the influence of gravity with the stem 11 following it, for a portion of the latch 27 still underlies the catch or keeper 26. During the downward travel of the stem 11 the follower pin 13 drops to the fall 14 and in sliding downwardly along the profile of this wall causes the stem 11 to rotate through substantially another 90°, thereby bringing the latch 27 completely out of registration with the keeper 26 so that the damper 3 can rotate in counter-clockwise direction to its fully opened position. The damper is maintained in its open position due to the weight of the spacer 25.

In the open position of the damper, the right end of the follower pin as viewed in Figs. 2 and 3 rests in the notch 15 of the lower profile of the cam track. To close the damper and lock it in its closed position, the right-hand end of the damper as viewed in Fig. 1 is pulled downwardly so as to bring its left-hand end into engagement with the seat 23 of the latch stem 11. The latch stem 11 moves upwardly in response to the upward movement of the left-hand end of the damper and momentarily rises only vertically without any rotary movement. When, however, the right end of the follower pin 13 engages the rise of the upper profile of the cam track immediately to the left of its apex 15a as viewed in Fig. 2, the further upward movement of the stem 11 is accompanied by a clockwise rotary movement through an angle of about 90°. During this interval of time, the pull on the cable 5 has been discontinued to thereby permit the left-hand end of the damper to start to fall, and with it the stem 11. Upon the downward movement of the stem 11 the follower pin 13 drops from the notch 17a of the upper profile to the fall 14 of the lower profile, whereupon the further downward movement of the stem is accompanied by a clockwise rotary movement of a further 90° angle. In this position of the stem 11 and the follower pin 13, the latch 24 completely underlies the keeper 26 thereby locking the damper 3 in its closed position across the flue 1.

In recapitulation, each upward movement of the valve stem is accompanied by a clockwise rotary movement thereof to the extent of 90°, and each downward movement thereof is likewise accompanied by a clockwise rotary movement of 90°. Since the latch 24 subtends an angle of substantially 180°, each complete cycle of movement of the latch stem 11, that is, one upward movement and one downward movement, will cause the latch 24 to either assume a position in complete registration with the keeper 26 or a position completely out of registration therewith. As shown in dotted line in Fig. 1, the first rotary movement of the latch 24 from its fully closed position does not serve to bring it out of complete registration with the keeper 26, but only partially so. It is the second rotary move-

ment of the latch in response to the downward movement of the latch stem 11 which serves fully to disengage or rotate the latch 24 out of registration with the keeper 26.

5 Although the cam track 12 includes two pairs of diametrically opposed hills and valleys, actually only one pair is required so long as the follower pin 13 extends outwardly from both sides of the latch stem 11 and so long as the cam blank 10 only extends halfway around the latch stem 11. It is only when the follower pin 13 extends from only one side of the latch stem that both pairs of hills and valleys are required.

The modification shown in Fig. 5 is generally 15 similar to the structure above described with reference to Figs. 1 to 4 inclusive. Like the previous modification, resort is had to a bracket generally designated by the reference numeral 31 arranged to be riveted or otherwise secured

20 to the inner wall of the flue 1 in a vertical position. However, in this modification the cam track generally designated by the reference numeral 32 is formed integral with the latch stem 33 and rotates therewith. The profiles of

25 the upper and lower walls of the cam track 32 are identical with the profiles of the cam track 12 of the modification shown in Figs. 1 to 4 inclusive. Since the cam track is made integral with the stem 33 and rotates therewith, the fol-

30 lower pin 34 is mounted on the rear wall 35 of the bracket 31 and is consequently stationary. In both modifications, however, there is of course a relative movement between the cam track and the follower pin. In the first modification the 35 cam track is stationary and the follower pin rotates with the latch stem, whereas in the latter modification the follower pin is stationary and the cam track rotates. Except for this difference with respect to the cam track and the follower

40 pin, and the details of construction of the bracket 31 and the blank from which it is die-stamped, the two modifications are identical and serve to rotate their corresponding latches through 180° in response to each upward and downward travel of the latch stem.

45 In the modification shown in Fig. 6, resort is had to a bracket generally designated by the reference numeral 41 in which a latch stem 42 is journaled for rotary movement therein and also for limited vertical movement. The required rotary movement of the latch stem 42 is produced by a pair of longitudinally spaced cam pin followers 43 and 44, carried by the latch stem 42 and arranged to travel along cam profiles 45 and 46 formed on the upper and lower ends of a cam cylinder 47. The cam cylinder 47, of course, circumscribes the latch stem 42 and is rigidly mounted on the lower arm 48 of the bracket 41. Generally, the profile 45 is comple-

50 mentary to the profile 46, although as in the case of the two modifications previously described, the notches of the profile 45 complementary to the points or apexes of profile 46 are offset laterally so as to insure the rotation of the latch stem 42 in the same direction (clockwise as shown in the two previous modifications described).

55 I claim:

1. A device of the character described comprising: a flue; a damper pivoted to and within said flue for rotation on an horizontal axis; a bracket member secured to and within said flue above the horizontal plane including said axis and in the path of rotation of said damper; a latch stem member journaled in said bracket on

60

65

70

75

a vertical axis for rotation and limited longitudinal movement therein; a radially extending latch secured to the lower end of said stem member; a catch secured to the upper face of said damper in vertical alignment with said latch when said latch is directed inwardly of said flue; and cam track and cam follower means associated with said stem member for causing said stem member to rotate through substantially 180° in response to each cycle of upward and downward movement thereof.

2. A device of the character described comprising: a flue; a damper pivoted to and within said flue for rotation on an horizontal axis; a bracket member secured to and within said flue above the horizontal plane including said axis and in the path of rotation of said damper; a latch stem member journaled in said bracket on a vertical axis, said stem being arranged for limited longitudinal movement relative to said bracket; tortuous cam tracks circumscribing said latch stem member and fixed to one of said members; cam track follower means secured to the other of said members in operative association with said cam tracks; a sector-shaped latch secured to the lower end of said latch stem and extending radially therefrom; and a catch secured to said damper in vertical alignment with said latch when said latch is directed inwardly of said flue.

3. A device of the character described comprising: a flue; a damper pivoted within said flue for rotation on an horizontal axis; a bracket member mounted to and within said flue above the horizontal plane including said axis and in the path of rotation of said damper; a stem member mounted in said bracket member for rotation and vertical sliding movement therein; a tortuous cam track circumscribing said stem member and secured to one of said members; a cam follower pin secured to the other of the members with a portion thereof disposed within the confines of said tortuous cam track; a sector-shaped latch fixed to the lower end of said stem member radially thereof for rotation and vertical movement therewith; and a catch fixed to the upper face of said damper in vertical alignment with said latch when said latch is directed inwardly towards the center of said flue.

4. A device of the character described comprising: a flue; a damper pivoted to and within said flue for rotation on an horizontal axis; a bracket member secured to and within said flue above the horizontal plane including said axis and in the path of rotation of said damper; a latch stem member journaled in said bracket on a vertical axis for rotation and limited longitudinal movement therein; a radially extending latch secured to the lower end of said stem member; a catch secured to the upper face of said damper in ver-

tical alignment with said latch when said latch is directed inwardly of said flue; and a vertically tortuous cam track surrounding said stem member and secured to said bracket members; and a cam follower disposed in said cam track and secured to said stem member, said cam track including a pair of opposed hills and valleys of such contour that said stem is caused to rotate substantially 180° in response to the up and down movement of said cam follower in one pair of the adjacent hills and valleys of said cam track.

5. A device of the character described comprising: a flue; a damper pivoted to and within said flue for rotation on an horizontal axis; a bracket member secured to and within said flue above the horizontal plane including said axis and in the path of rotation of said damper; a latch stem member journaled in said bracket on a vertical axis for rotation and limited longitudinal movement therein; a radially extending latch secured to the lower end of said stem member; a catch secured to the upper face of said damper in vertical alignment with said latch when said latch is directed inwardly of said flue; opposed and complementary cam tracks fixed to said bracket member about said stem member, each of said cam tracks being provided with two pairs of contiguous hills and valleys; and a pair of cam track follower pins extending diametrically through said stem member with the ends thereof in sliding contact with said cam tracks.

6. A device of the character described comprising: a flue; a damper pivoted to and within said flue for rotation on an horizontal axis; a bracket member secured to and within said flue above the horizontal plane including said axis and in the path of rotation of said damper; a latch stem member journaled in said bracket on a vertical axis for rotation and limited longitudinal movement therein; a radially extending latch secured to the lower end of said stem member; a catch secured to the upper face of said damper in vertical alignment with said latch when said latch is directed inwardly of said flue; a cam track secured to and surrounding said stem member, said cam track including two pair of contiguous hills and valleys; and a follower pin mounted on said bracket with its free end disposed in said cam track.
